ROOM DIVIDER

Janice K. Wilkin, % Marine Memorial Club,
609 Sutter St., San Francisco, Calif.

Filed Aug. 14, 1963, Ser. No. 76,206

Term of patent 14 years

(Cl. D33—1)

FIG. 1

The top of the room divider is conventionally flat.

I claim:

The ornamental design for a room divider, as shown.
